(57) **CLAIM**

The ornamental design for a carrying bag for a survey rod, as shown and described.

DESCRIPTION

FIG. 1 is a perspective of a carrying bag for a survey rod;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear end view thereof;

FIG. 7 is a front end view thereof;

FIG. 8 is an enlarged fragmentary perspective of a portion of the carrying bag indicated in FIG. 1 showing a cap in a closed position; and,

FIG. 9 is a perspective similar to FIG. 8 but showing the cap in an opened position.

1 Claim, 8 Drawing Sheets
